UNITED STATES PATENT OFFICE.

ARNOLD E. DE FRANCE, OF TOLEDO, OHIO.

SWITCH-MOUNTING.

No. 892,410.

Specification of Letters Patent.

Patented July 7, 1908.

Application filed October 4, 1907. Serial No. 395,817.

To all whom it may concern:

Be it known that I, ARNOLD E. DE FRANCE, of Toledo, county of Lucas, and State of Ohio, have invented certain new and useful

5 Improvements in Switch-Mountings; and I do hereby declare that the following is a full, clear, and exact description thereof, which will enable others skilled in the art to which it appertains to make and use the same, reference being had to the accompanying drawings, and to the figures of reference marked thereon, which form part of this specification.

10 This invention has reference to improved means for mounting snap switches, and the same embodies the novel combination, arrangement and details of construction hereinafter shown, described and claimed.

15 In the accompanying drawings, illustrative of a preferred embodiment of the invention, Figure 1 is a plan view of the switch mounting as it appears when plastered in upon a wall in readiness to receive a snap switch, the wire terminals and the flexible covering 20 therefor being shown in position; Fig. 2 is a cross section of the same on line $x-x$ in Fig. 1, the switch being shown partly in elevation; Fig. 3 is a plan view of the mounting in 25 position before the wall is lathed and plastered; and Fig. 4 is a plan view of the bottom plate of the mounting showing the means for fastening the flexible covering for the wire 30 terminals.

35 Referring to the details, 1 is a bottom plate of substantially rectangular outline and the same is provided with a plurality of perforations 3, 3, 3, 3 through which the flexible covering or tubing 4 for the wire terminals are directed, and the margins 5 of the perforations are deflected from the plane of the 40 plate 1 to provide a plurality of engaging tongues 6 around each perforation adapted to firmly embrace the flexible covering and hold the same from being withdrawn after 45 insertion through the perforations. Mounted upon the bottom plate and extending outwardly therefrom is a sheet metal box-like inclosure 7 of substantially cylindrical form and open at the front and rear, the top 50 margin 8 of the sides serving as a support for the switch 9, and extending inwardly at opposite points from the top margin 8 of the inclosure are integral lugs 10 having threaded perforations 11 to be engaged by ordinary screws 12 passing through the base of the 55 switch and securing the same in place.

The box-like inclosure 7 is also provided with integral lugs 13 extending outwardly from its lower margin, the ends of the lugs fitting within the upturned margins 13' of the 60 corners of the bottom plate, and both the bottom plate and the lugs 13 are provided with registering perforations through which screws 14 are directed to secure the bottom plate and the inclosure 7 in assembled relation 65 upon a wall.

The complete device is shown in position in Fig. 3, the same being secured to the usual cross pieces *a* nailed crosswise between the studding of a wall. As thus shown the device is in readiness to receive the flexible tubing or covering for insulated wire terminals. After these have been placed in position the wall is lathed and plastered as shown in Figs. 1 and 2, the top margin of the inclosure for 70 the terminals being flush with the plaster. The switch after being placed in position upon the inclosure is extremely rigid, being however capable of removal when required by removing the screws which engage the 75 lugs 10. The device as shown is constructed entirely of sheet metal, and is consequently simple and inexpensive to manufacture.

What I claim is:

80 In a mounting for snap switches, a flat sheet metal bottom plate of substantially 85 rectangular outline having upturned margins and provided with perforations to receive, and holding means to secure, flexible tubing, and a sheet metal inclosure of substantially 90 cylindrical form mounted upon the bottom plate, the inclosure being open at the front and rear and provided with integral extensions at its rear margin of substantially 95 rectangular shape and dimensions to fit within the upturned margins of the bottom plate, inwardly extending integral lugs at the top margin of the inclosure providing fastening means for a switch, and means for securing the bottom plate and the inclosure in assembled 100 relation upon a wall, substantially as described.

In testimony, that I claim the foregoing as my own I affix my signature, in presence of two witnesses.

ARNOLD E. DE FRANCE.
